UNITED STATES PATENT OFFICE

151,681

DESIGN FOR A SELF-SERVICE REFRIGERATED DISPLAY CASE

Edward F. Brill, Milwaukee, Wis.

Application April 15, 1946, Serial No. 128,595

Term of patent 3½ years

(Cl. D80—11)

To all whom it may concern:

Be it known that I, Edward F. Brill, a citizen of the United States, residing at Milwaukee, in the county of Milwaukee and State of Wisconsin, have invented a new, original, and ornamental Design for a Self-Service Refrigerated Display Case, of which the following is a specification, reference being had to the accompanying drawing, forming a part thereof.

In the drawing:

Figure 1 is a perspective view of a self-service refrigerated display case with the doors and transparent pane members in closed position and showing my new design; and

Figure 2 is a perspective view similar to Figure 1 with one of the doors in open position.

I claim:

The ornamental design for a self-service refrigerated display case, substantially as shown.

EDWARD F. BRILL.
